UNITED STATES PATENT OFFICE.

SPENCER NEEMES, OF TROY, NEW YORK, ASSIGNOR TO NEEMES BROS.,
OF TROY, NEW YORK, A FIRM.

GRATE.

No. 822,296.

Specification of Letters Patent.

Patented June 5, 1906.

Application filed August 19, 1903. Serial No. 169,968.

To all whom it may concern:

Be it known that I, SPENCER NEEMES, a citizen of the United States, residing at Troy, county of Rensselaer, and State of New York, 5 have invented certain new and useful Improvements in Grates, of which the following is a specification.

The invention relates to such improvements; and it consists of the novel construction and combination of parts hereinafter described and subsequently claimed.

Reference may be had to the accompanying drawings, and the reference characters marked thereon, which form a part of this 15 specification. Similar characters refer to similar parts in the several figures therein.

Figure 1 of the drawings is a vertical longitudinal section taken on a plane indicated by broken line 11 in Fig. 2 and showing the relative position of the grate when in use. Fig. 2 is a top plan view of the grate and end tables. Fig. 3 is a side elevation of the grate-frame detached with the end tables removed. Fig. 4 is a sectional view similar to that in Fig. 1, 20 showing the back section of the grate in a dumping position. Fig. 5 is a similar fragmentary view showing the front section of the grate in a shaking position. Fig. 6 is a similar view of two back grate-bars, showing 25 an oscillatory movement of twenty-two and one-half degrees. Fig. 7 is a similar view of two front grate-bars, showing an oscillatory movement of twenty-two and one-half degrees. Fig. 8 is a view in side elevation of one 30 of the grate-bars broken away at each end and showing part of the dumping connections. Fig. 9 is a side elevation of one of the bearing-blocks detached.

My invention is especially applicable to 40 grates employed in furnaces used in connection with steam-boilers to generate steam for power or heating purposes. When such grates are employed in connection with inclined tubular boilers, as well as horizontal 45 boilers, in some cases the grate is inclined from the front to the back, so that the back end of the grate is lower than the front end. I have ascertained that improved results may be obtained if one-half or more of the grate, 50 including the back end, is so constructed that it can be dumped by the oscillatory movements of rocking grate-bars, while the front portion of the grate is adapted for shaking instead of dumping by an oscillatory move-

ment of smaller rocking grate-bars, so as to 55 grind up the clinkers and allow the broken pieces, together with the ashes, to fall through the comparatively small openings in the grate without dumping the fire. The larger portion of the grate, including the back, is thus 60 cleared of ashes and clinkers in a comparatively short time and with little effort, while the comparatively smaller front portion of the grate can be cleared of ashes and clinkers by the shaking process, which can be carried 65 to any degree desired to produce an approximately even draft throughout all portions of the grate.

Referring to the drawings, I have shown in Fig. 1 a vertical section of the front portion of the furnace, including the front end of steam-boiler 1, combustion-chamber 2, having a feed-opening 3, ash-pit 4, bridge-wall 5, and grate 6.

The rear ends of the side bars 7 of the grate-frame are supported by a bar 8, end-seated in the side walls, and is lower than the other end, which is supported by the bar 9.

The grate comprises a dumping-section, 75 consisting of about two-thirds of the grate, including the rear end, and a shaking-section, 80 consisting of the remaining one-third at the front end of the grate. The shaking-section is made up of a row of four rocking or oscillatory grate-bars 12 and the stationary resistance-bars 13, the stationary bars alternating 85 with the oscillatory bars, as shown. The oscillatory bars are severally provided at each end with a trunnion 14, the trunnion at one end resting in a detachable bearing-block 15, 90 dovetailed into a side bar of the grate-frame, and the trunnion at the other end having its bearing in the opposite side bar of the frame. The resistance-bars 13 are supported at their 95 ends in suitable apertures 16 in the side bars of the grate-frame. Projecting from the lower edge of the oscillatory grate-bars are the lugs 17, which are connected, by means of pivots 18, with a shaking-bar 19, the latter being connected by link 20 with the shaking-lever 21, 100 pivoted at 22 upon a bracket 23, secured by bolts 24 to the front wall 25 of the ash-pit, as seen in Fig. 1. The lever 21 is provided at its upper end with a socket 26, adapted to receive one end of a detachable lever. (Not 105 shown.) The rear section of the grate is made up of similar oscillatory grate-bars 30, without the interposition between each pair of

bars of a stationary resistance-bar. The oscillatory bars 30 are made much wider than the bars 12 and are severally provided with similar means for oscillating the same, consisting of the attaching-lugs 31, secured by pivots 32 to the dumping-bar 33, which latter bar is pivotally connected by link 34 with the actuating-lever 35, fulcrumed at 22 upon the bracket 23 and provided with a separate socket 36, adapted to receive an actuating detachable lever. (Not shown.)

A coal-fire having been started and maintained over the entire surface of the grate in the usual well-known manner, the operation of the grate is as follows: When the accumulation of ashes on the front section of the grate is sufficient to retard the draft through that section and reduce its heating capacity below that of the same area in the rear section, the shaking operation hereinbefore described is applied to the front section until a sufficient quantity of ashes has fallen through this section to restore the normal draft and raise its heating capacity to that of the rear section, which operation may be repeated as required until the accumulation of ashes in the rear section is sufficient to reduce the draft of that section below the normal, whereupon the fire or live coals upon the rear section are drawn forward upon the front section, after which the rear section is dumped, as hereinbefore described. Then after the grate-bars of the rear section have been restored to their normal position, such as shown in Fig. 1, the fire or live coals which have been removed to the front are forced back again and distributed over the dumping-section of the grate and new fuel applied as desired. It is thus possible to maintain approximately the same heating capacity throughout all parts of the combustion-chamber, the shaking operation being applied to the front section of the grate from time to time, as required.

As a means for facilitating the operation of cutting or crushing any clinkers or hard lumps which may accumulate beneath the fire and on the grate-surface I give the oscillatory grate-bars an improved form, which consists in making the sides of the bars concaved, forming clinker-pockets 39. I have demonstrated by experiment that when the sides of the oscillatory members are concaved the clinkers or hard lumps falling into the spaces between such concaved surfaces and the neighboring resistance-bar, as shown by dotted lines 40 in Fig. 5, would not slip out from between the edge of the concaved bar and the resistance-bar, but would be crushed by the oscillatory movement of the bars, and the fragments would fall down between the bars through the grate. The dotted lines 41, Fig. 5, represent a lump resting on the upper surface of a resistance-bar, and an oscillatory bar. Such a lump would re-

main in the position shown while the bars are being oscillated by a movement of the shaker-bar 19 to the left until a neighboring edge of the oscillatory bar passed from under the lump, whereupon the lump would occupy a position relatively to the oscillatory and resistance bars like that of the lump 40, after which an oscillatory movement of the bar in the opposite direction would crush it, as before described, whereas if the concaved surface was a plane surface the lump would be more likely to slide upward from between the stationary and oscillatory bars without being crushed, or would be only partially crushed, requiring a prolonged shaking operation to pass the lumps down through the grate. By having the sides concaved the operation is accomplished much more speedily and with greater certainty. It sometimes happens that clinkers and lumps will form of sufficient size to prevent their passing readily through the large openings between the oscillatory grate-bars of the dumping-section, in which a lump might assume the position shown by the dotted lines 42 in Fig. 4. By having the sides of these oscillatory bars concaved the lump would be caught between the sharp edges of the bars and crushed sufficiently to pass through the opening upon giving the bars two or three oscillatory movements.

In Figs. 4 and 5 the bars are shown oscillated at an angle of forty-five degrees and in Figs. 6 and 7 at an angle of twenty-two and one-half degrees, which diagrammatically represent two of the differing relative positions assumed by the neighboring oscillatory grate-bars during their crushing movements.

The grate-bars are provided with teeth 50, affording spaces 51 between the teeth through which the air passes up to the fire.

The rear table 52 is supported by the side bars 7 of the grate-frame and may contain more or less draft-openings 53. The front table 54 extends from the grate out to the front wall of the furnace in two sections.

The wall-bars 55 and 56 are detachably inserted between the sides of the grate and the furnace-walls, and may be adapted to resist the end thrust of the grate-bars.

What I claim as new, and desire to secure by Letters Patent, is—

1. A furnace-grate comprising a back section of relatively large area made up of relatively wide oscillatory grate-bars, a front section of relatively small area made up of relatively narrow oscillatory grate-bars, and means for communicating oscillatory movements to the bars of either section independently of the other, substantially as described.

2. A furnace-grate comprising a back section made up of parallel oscillatory bars; a front section made up of parallel bars which are alternately stationary and oscillatory, and means for communicating oscillatory

movements to the movable bars of either section independently of the other, substantially as described.

3. A furnace-grate comprising a back section made up of grate-bars parallel with each other and oscillatory to present relatively large openings through the grate, a front section made up of grate-bars parallel with each other and oscillatory to present relatively small openings through the grate, and means for communicating oscillatory movements to the bars of either section independently of the other, substantially as described.
4. A furnace-grate comprising a back section made up of grate-bars parallel with each

other and oscillatory to present relatively large grate-openings, a front section made up of movable and stationary grate-bars alternating, and parallel, with each other, the movable bars being oscillatory to present relatively small grate-openings, and means for communicating oscillatory movements to the movable bars of either section independently of the other, substantially as described.

In testimony whereof I have hereunto set my hand this 14th day of August, 1903.

SPENCER NEEMES.
